JAMES D. SMITH, OF WASHINGTON, DISTRICT OF COLUMBIA.

DESIGN FOR FIGURES.

Specification forming part of Design No. 7,079, dated December 30, 1873; application filed December 15, 1873.
 [Term of Patent 14 years.]

To all whom it may concern:

Be it known that I, JAMES D. SMITH, of Washington, in the county of Washington and District of Columbia, have invented a Design for Figures, of which the following is a specification:

The nature of my design is fully represented in the accompanying drawing, to which reference is made.

The design consists essentially of figures or numbers thickened up or swelled at about the points shown, which are in figures as at present formed the finest or thinnest points. The result of the design is the rendering impossible of the altering of any figure or figures by erasure of any part or the whole thereof, and rewriting or printing over the erasure, for, as will be observed in any given figure, the swelled or thickened portion, if erased, cannot be covered by any line of any other figure to which it is desired to make the change, as a thin line necessarily occupies the locality from which the swelled line was erased, and thus exposes the attempt at alteration.

I am aware that figures have been made having at some portion thereof a swelled or thickened appearance.

The distinctive character of my design for a series of figures is found in the swelled portion located so that the alteration to or substitution of another figure will necessarily bring the thinnest lines of the altered or subsequent figures over or upon the points or position occupied by the thinnest lines of the first or original one.

What I claim as my invention is—

A design for figures composed of thick and thin lines relatively to each other, substantially in the manner above described.

Witness my hand and seal this 12th day of December, A. D. 1873.
